UNITED STATES PATENT OFFICE.

OLIVER D. HUNT AND BERTHA HUNT, OF COLUMBUS, OHIO, ASSIGNORS TO
THE GEORGE B. DONAVIN & COMPANY, OF COLUMBUS, OHIO.

DESIGN FOR A STOVE.

SPECIFICATION forming part of Design No. 36,658, dated December 1, 1903.

Application filed September 29, 1903. Serial No. 175,101. Term of patent 7 years.

To all whom it may concern:

Be it known that we, OLIVER D. HUNT and
BERTHA HUNT, citizens of the United States,
residing at Columbus, in the county of Frank-
5 lin and State of Ohio, have invented a new,
original, and ornamental Design for Stoves,
the same being disclosed in the accompany-
ing drawing, in which the figure is a perspec-
tive view of a stove made in accordance with
10 said design.

What we claim as new, and desire to secure
by Letters Patent, is—

The ornamental design for a stove, as here-
in shown.

In testimony whereof we have signed our 15
names to this specification in the presence of
two subscribing witnesses.

OLIVER D. HUNT.
BERTHA HUNT.
